UNITED STATES PATENT OFFICE.

LOUIS A. PERROTTET AND EDOUARD ANGLY, OF NEW YORK, N. Y.; SAID ANGLY ASSIGNOR TO SAID PERROTTET.

COMBINED LIGHT-INCREASING DEVICE AND SMOKE-BELL.

SPECIFICATION forming part of Letters Patent No. 637,027, dated November 14, 1899.

Application filed April 15, 1899. Serial No. 713,216. (No model.)

To all whom it may concern:

Be it known that we, LOUIS A. PERROTTET and EDOUARD ANGLY, citizens of the United States, residing in New York, in the county 5 of New York and State of New York, have invented certain new and useful Improvements in a Combined Light-Increasing Device and Smoke-Bell, of which the following is a specification.

10 This invention relates to a combined light-increasing device and smoke-bell; and it more particularly relates to an improved means for increasing the light of a gas or other lamp, while at the same time it effectively saves the 15 use of such gas.

The object of the invention is to provide a light-increasing device which can be quickly and easily disposed in position to effect the result desired and which will be simple in 20 construction and without complicated parts or mechanism, and will, moreover, not only increase the light, but at the same time materially save the amount of gas used.

Another object of the invention is to provide a light-increasing device and a coöperating instrumentality—such, for instance, as a smoke-bell—one carried by the other, and which in practice may be detachable one from the other, and which improvement is intended 30 to be simple in its construction, durable in use, and effective to accomplish the purpose for which it is designed, while at the same time is intended to be inexpensive to manufacture, so that the same can be furnished at 35 a comparatively low cost.

In the drawings accompanying and forming part of this specification, Figure 1 is a side elevation, partly in section, of a Welsbach burner attached to an ordinary gas-jet 40 with this improved combined light-increasing device and smoke-bell disposed in position relatively thereto. Fig. 2 is a sectional view of the upper portion of one form of chimney with this improved light-increasing device 45 in position thereon and detached from the smoke-bell. Fig. 3 is a perspective view of this combined device detached from the chimney, and Fig. 4 is a side view of one of the brackets for assembling the smoke-bell and 50 light-increasing device.

Similar characters of reference designate like parts in all the figures of the drawings.

This improved device for increasing the light and at the same time saving the gas comprises in a general way a device adapted 55 to be placed in the top of a chimney or globe and of such shape that it may be placed without adjustment into various sizes of chimneys and of such structure that it is apprehended it will prevent the ready escape of the gas- 60 eous fluid, and thereby accomplish the object desired.

In the form shown the light-increasing device A is conical in shape, whereby it can be disposed in various sizes of chimneys, the 65 lower end thereof being provided with an opening 2, which may be of different sizes, in accordance with the amount of increase desired—that is to say, the larger the opening the less the increasing power of the device. 70 In some forms we may make the opening half an inch in diameter, while in others it may be an inch in diameter. Openings of other diameters, however, may be used, as found desirable and preferable in practice. This cone-shaped device may be formed as an integral structure; but in the form shown its edges 3 overlap, being secured together by some suitable fastening devices 4. Carried by this device is the smoke-bell B, which may be of 75 80 any suitable construction; but in the form shown it is also conical in shape, whereby it will assist the effectiveness of the light-increasing device. This smoke-bell may likewise be made as an integral structure; but in 85 the form shown its edges 5 overlap, being also secured together by some suitable fastening devices 6.

In practice the smoke-bell B and the light-increasing device A may be rigidly or integrally connected; but in the form shown they are detachably secured together, the smoke-bell being supported by the light-increasing device through the instrumentality of brackets or arms 8, (shown herein as three in number,) each provided with a pair of slotted or recessed ends 9 and 10 to receive the edge of the light-increasing device and the edge of the smoke-bell, and in the construction shown these brackets have the material forming the 90 95 100

same (usually metal) bent upon itself at each end thereof in such manner as to form a bifurcated end. Each of these brackets has its upper bifurcated end 10 extending substantially in alignment with the curved part of the bracket, while its lower bifurcated end 9, which is adapted for attachment to the light-increasing device, projects at an angle to the curvature of the bracket, the intermediate parts 12 of such brackets or arms curving outwardly.

In practice the smoke-bell may be constructed of any suitable material adapted for the purpose—such, for instance, as mica—and this may also be the case with the light-increasing device—as, for instance, mica or brass. Furthermore, both of the devices may have reflecting-surfaces, if found desirable.

The device is illustrated as disposed in position relative to a Welsbach burner, having the usual mantle and straight cylindrical chimney 13. While other forms of chimneys may be used, provided the device can properly fit therein so as to secure the effect desired, we have found, however, in actual practice that the straight cylindrical chimney will give a highly-superior result. The device, however, is adapted for all ordinary kinds of burners having chimneys.

30 We apprehend that in operation this improved light-increasing device, owing to its construction, reduces the outlet from the chimney, the conical form thereof having a peculiar effect in controlling the flow of gas 35 within the chimney, since such gas passes around the outside of the cone A, which projects into the chimney, and is finally turned in and compelled to pass downward in order to emerge from the center of the cone, so that 40 the gas is confined for a longer period within the chimney than would otherwise be the case, thereby increasing the completeness of combustion, and consequently increasing the illumination resulting from a given amount 45 of gas. We also apprehend that this improved device, owing to its construction and disposition with relation to the light-increasing device, shuts off a large part of the draft through the chimney, thereby preventing the 50 ready escape of the gas, which, as is well known, ordinarily escapes rapidly and prevents complete combustion. Hence this smoke-bell coöperates with the light-increasing device to thereby insure a more complete combustion. Furthermore, in the use 55 of this improved device in connection with a smoke-bell of the construction set forth the upwardly-passing gases after passing the cone strike the under side of the bell B and are 60 thereby deflected, thus heating a transversely-wide region of the air above the chimney and so tend to intercept the upward flow of cold air outside of the chimney, all of which tends to keep the entire chimney and the entire 65 space within the same most nearly of the same temperature.

Having described our invention, we claim—

1. In combination, with a lamp-chimney, a smoke-bell and light-increasing device connected together, said light-increasing device comprising a member having an opening adjacent to its lower end and projecting into said chimney and supported by the edge thereof and effective to secure a more complete combustion of the gases by partially 70 confining the same therein, and said bell having its lower edge free of engagement with said light-increasing device.

2. In combination, with a lamp-chimney, a light-increasing device comprising a member 80 having an opening at its under side and projecting into said chimney and supported by the edge thereof and effective to secure a more complete combustion of the gases by partially 85 confining the same therein, and a coöperating instrumentality supported by the light-increasing device above the same and having its lower edge free of engagement with said light-increasing device.

3. In combination, with a lamp-chimney, a 90 conically-shaped instrumentality provided with an opening adjacent to its apex and having its apex end inserted into the upper end of said chimney, and a flaring instrumentality supported by said conically-shaped instrumentality above said chimney and having its lower edge free of engagement with 95 said light-increasing device.

4. In combination, with a lamp-chimney, a 100 pair of coöperating instrumentalities connected together, one a light-increasing device comprising an open-ended conically-shaped member projecting into said chimney and supported by the edge thereof, and the other formed independently of and supported above 105 said light-increasing device.

5. A light-increasing device comprising a cone-shaped member adapted to have that end thereof having the smallest diameter project into a chimney and provided adjacent to 110 its apex with an opening, and a smoke-bell connected to said member and supported above that part thereof having the largest diameter, and having its lower edge free of engagement with said light-increasing device. 115

6. A light-increasing device comprising a cone-shaped member adapted to have that end thereof having the smallest diameter project 120 downwardly into a chimney and provided adjacent to its apex with an opening, and a smoke-bell detachably connected to said member and supported above the same.

7. A lamp attachment comprising a cone-shaped member adapted to have that end thereof having the smallest diameter project 125 downwardly into a chimney and provided adjacent to its apex with an opening, and an instrumentality connected thereto and supported above that end thereof having the largest diameter with its lower edge free of 130 engagement therewith and effective to coöperate with said cone-shaped member.

8. In combination, with a lamp-chimney, a light-increasing device comprising a con-

ically-shaped instrumentality provided with an opening at the under side and adapted for insertion into the upper end of said chimney; a conically-shaped smoke-bell detachably secured to said light-increasing device; and removable brackets for connecting said smoke-bell and light-increasing device.

9. A lamp attachment comprising a cone-shaped member having an opening therein adjacent to its apex and adapted for insertion with its apex end extending downwardly and into a lamp-chimney; an instrumentality connected thereto and co-operating therewith; and a plurality of arms or brackets connecting said instrumentality with said light-increasing device.

10. A light-increasing device comprising a cone-shaped member having an opening therein adjacent to its apex and adapted for

insertion into a lamp-chimney; a smoke-bell supported above that part of said member having the largest diameter; and removable brackets for securing said smoke-bell to said conical member.

11. A light-increasing device comprising a conically-shaped member having an opening therein adjacent to its apex and adapted for insertion into the top of a chimney; a conically-shaped smoke-bell disposed above that part of said member having the largest diameter; and brackets provided with bifurcated ends for connecting said member and smoke-bell.
